FRANK E. HALLORAN, OF BROOKLYN, NEW YORK.

RADIO RECEIVING SYSTEM.

Application filed November 10, 1925. Serial No. 68,067.

This invention relates to a dial control for radio receiving systems.

Modern radio receiving systems are constructed of parts having such electrical characteristics as to provide for extremely high selectivity in the reception of radiant energy. Systems of this kind usually employ combinations of inductance and capacity, either or both of which may be adjustably varied to bring the circuit into tune or resonance to a desired electrical frequency. Such a variable element then controls the electrical resonance of the receiving system, and it is one object of the present invention to provide an improved dial control for such utilities whereby extremely fine and sensitive adjustments thereof may be readily obtained.

Another object of the invention is to provide improved adjusting means for such utilities which may be accurately readjusted to positions previously obtained, thereby to enable the operator to receive a signal at a predetermined setting of the control.

Still another object of the invention relates to an improved dial control in which back lash and lost motion is effectively minimized.

A feature of the invention relates to the provision of a dial control having a plurality of series of graduations, and means for indicating thereby the adjustment of the utility, with extreme accuracy.

The invention is also particularly applicable to the control of a rheostat in a radio receiving system.

Other objects will appear from the following description taken in connection with the accompanying drawings in which

Figure 1 is a diagrammatic representation of a radio receiving system embodying features of the invention;

Figure 2 is a plan view of the dial control for the tuning element of Figure 1;

Figure 3 is a sectional elevation taken on the line 3—3 of Figure 2 with the gears engaged;

Figure 4 is a side elevation of the dial control of Figure 2;

Figure 5 is a sectional view taken on the line 5—5 of Figure 2 with some of the gears in disengaged position;

Figure 6 is a plan view of a modified form of the dial control;

Figure 7 is a sectional elevation and Figure 8 a side elevation of the dial control of Figure 6.

Like reference characters refer to like parts in the several figures of the drawings.

In the following description and claims parts will be identified by specific names for convenience of expression but they are intended to be as generic as their application to similar parts or equivalent constructions as the art will permit.

As an aid to the understanding of the invention, there is shown in Figure 1 of the drawings, a diagrammatic representation of a typical radio receiving system embodying features of the invention. Such a receiving system includes for example, an energy collecting device such as an antenna 10, connected in circuit with the primary 11 of a coupling 12 to ground 13. It is understood, however, that any other desired radiant energy responsive device may be employed, such as a Bellini-Tossi loop. In the embodiment shown, the secondary 14 of the coupling 12 is shunted by means of a variable condenser 15 forming in combination therewith a resonant circuit 16 which may be tuned by adjustment of the condenser 15 into resonance with a desired frequency, thus rendering the receiver selectively responsive to the desired signal wave. The resonant circuit 16 is connected by a conductor 17 and through a blocking condenser 18 to the input or grid of a three electrode thermionic device or vacuum tube 19 having a usual filament 20, grid 21, and plate 22. The filament 20 is heated by means of a filament battery 23, there being included in the circuit a rheostat 24 for controlling the filament current.

A conductor 25 extends from one pole of the battery 23 to the resonant circuit 16 for completing the input circuit of the tube 19. A high resistance grid leak 26 is provided in shunt with the blocking condenser 18. The plate 22 of the thermionic device 19 is included in circuit with an indicating device 27 which may take the form of a telephone receiver, and with a plate potential battery 28 for rendering the plate 19 electrically positive with respect to the filament.

The parts shown in Figure 1 may be mounted, in a conventional manner, on a panel 30 which may be mounted in any desired manner, as for example, on the front

of a cabinet forming a housing. The condenser 15 may be mounted upon a face of the panel 30 and may include a relatively stationary plate 31 and a movable sector 32 mounted on a rotatable shaft 33. The shaft 33 protrudes through an aperture in the panel 30 as shown in Figure 3 of the drawings. Similarly the rheostat 24 may be mounted on a face of the panel 30 and may include a relatively fixed resistance 34 and a movable contact brush 35 in contact with the resistance 34. The brush 35 is mounted on a rotatable shaft 133 one end of which protrudes through an aperture in the panel 30.

Referring to Figures 2 to 5 inclusive of the drawings, there is provided a flanged metal frame 40, shown as having a pair of apertured lugs 41, 41 on the periphery. The frame is affixed on a face of the panel 30 by suitable holding screws 42, shown as provided with hand nuts 43. The frame 40 is provided with a flange portion 44 offset into spaced relation with the face of the panel, in the form of a rack or internally toothed gear 45 (see Figure 2). The frame 40 thus forms effectively a fixed toothed gear, having a predetermined number of teeth therein.

Rotatably mounted within the flange portion 44 of the fixed gear 40 and in axial alignment therewith is a movable gear element comprising an indicating cylinder 50, formed of an insulating material such as a phenol compound, a metal hub 51 secured thereto by fastening screws such as 52, and a ring gear 53 secured to the indicating cylinder 50 by fastening screws or rivets such as 54. The hub 51 is mounted on the end of the shaft 33 and has an interior recess the inner face of which is screwthreaded for a portion of its depth. The movable ring gear 53 is provided with internal teeth and has its pitch cylinder of the same size as the pitch cylinder of the fixed gear 40, but is provided with a different number of teeth. Preferably these gears differ by one tooth, and in the embodiment shown the movable gear has a greater number of teeth than the loose gear. The pitch cylinders of the gears, however, are substantially in alignment. The peripheral surface of the cylinder 50 is provided with an index, such as the graduations 55. The frame 40 is cut away as at 56 (Figure 2) to form a sight hole through which the cylinder 50 can be observed, and is provided with an index, such as a line 57 (Figure 4) which registers with the graduations on the cylinder.

A radial drill hole is made as at 58 (see Figure 2) in the cylinder 50, and when it is desired to permit movement of the shaft 33 through only 180° of arc a pin 59 is inserted therein. The pin 59 contacts with the lugs 41, which thus form an abutment therefor.

The hole 58 is so positioned that when the pin 59 is brought up against one of the lugs 41, the zero graduation of the cylinder registers, at least approximately, with the index 57 on the fixed gear 40, and when the pin engages the other lug the 180° graduation of the cylinder 50 registers, at least approximately, with the index 57. By withdrawing the pin, however, the shaft 33 may have a free movement throughout the 360° of arc.

An indicating disc 60, formed of insulating material, is loosely mounted upon the hub 51, so as to be rotatable with respect thereto and with respect to the fixed gear 40. The face of the dial 60 may be bevelled as at 61 and provided with an index such as the graduations 62. The dial is provided with an eccentrically positioned hollow boss or projection 63, having a shouldered bore 64. The upper end of the projection 63 is notched and there is set in the notch so as to conform to the configuration of the projection, a metal sleeve 65 secured to the projection in any desired manner, as by a pin (not shown). The outer surface of the sleeve is provided with an index, which may include a series of graduations. In the bore 64 is slidably mounted a pinion 67 having external teeth cut with the same pitch as the teeth of the gears 40 and 53, and arranged to mesh therewith. The pinion 67 is provided with a shouldered hub 68 of restricted diameter extending through a corresponding aperture 69 in the dial 60 and into the relatively larger bore 64 of the projection 63. The outer end 70 of the hub 68 of the pinion is of still more restricted diameter, and there is affixed thereto, as by means of a pin, a button 71. The periphery of the button is knurled, but is filed down to a smooth surface at one portion 72, where an index, such as a line 73 is provided, for a purpose which will be subsequently set forth. The top face of the button 71 is formed with a concave surface, for greater convenience in operating. The hub 68 is free to slide in the aperture 69, and the pinion is normally yieldingly maintained in the position shown in Figure 3 by a coiled spring 74 positioned in the space between the wall of the bore 64 and the hub 68, the spring presing against the button 71 at one end. The bottom of the bore 64 serves as an abutment for the other end of the spring. In the normal position shown, the teeth of the pinion 67 engage the teeth of both the fixed gear 40 and the rotatable gear 53, the width of its teeth being sufficient for this purpose. By depressing the button 71 the pinion 67 can be moved down out of engagement with the teeth of the fixed gear 40. The pitch cylinder of the pinion 67 is in alignment at the point where the teeth are

in mesh, with the pitch cylinders of the gears 40 and 53.

For maintaining the hub 51 in position on the shaft 33, there is provided a friction band 80, formed preferably of soft rubber, adapted to fit around the shaft 33, and within the recess in the hub 51. A metal nipple 81, having a bore for the shaft 33, and partially screwthreaded on its exterior to engage the internal threads of the hub 51 is provided with a flange or skirt 82 to compress the friction band 80. The upper portion of the nipple 81 is provided with a hexagonal flange of relatively enlarged diameter, and is held in a thumb screw 83 by means of a metal washer having its edges ridged so as to be held in the button by being crimped therein, the button 83 being preferably formed of an insulating material such as a phenol compound. Thus the washer turns with the thumb screw 83 with respect to the hub 51.

The device is assembled by mounting the pinion 67 on the indicating disc 60, and after placing the spring 74 and the metal sleeve 65 in position, pinning the button 71 to the outer end 70 of the pinion hub 68 with the button 71 in contact with the shoulder of the main hub 68. The movable gear 53 and cylinder 50 are fastened together by the rivets 54, and are mounted on the hub 51 by screws 52. The indicating disc 60 with its pinion is then placed on the hub 51. The friction band 80 is inserted within the hub 51 and the thumb screw 83 and nipple 81 applied so as to maintain the dial on the hub 51.

The device is mounted by slackening off the thumb screw 83, the zero marks of the graduations lined up with their respective indices and held in position. The frame 40 is then held in central position with respect to the cylinder 50 by suitable cardboard feelers or thickness gauges, (not shown) inserted in gap 84, 84. The whole device is then set so that the hub 51 is on the shaft 33 with the friction band 80 around the shaft. The thumb screw 83 is then turned down so that the friction band 80 is subjected to pressure and flows around the shaft 33, gripping it tightly. The frame 40 is fastened to the panel 30 by the holding screws 42, 42 and nuts 43, and the cardboard feelers withdrawn.

In operation, a rough adjustment of the shaft can be obtained by placing the thumb or forefinger on the button 71 and light pressure brought to bear sufficient to overcome the tension of the spring 74 and to move the pinion 67 out of engagement with the fixed gear teeth 45. The indicating disc 60 may then be rotated carrying with it the movable gear 53, cylinder 50, hub 51 and rotating the shaft 33 at one-to-one ratio. It will be noted that the teeth of the pinion 67

remain in constant mesh with the teeth of the movable gear 53. The index mark 57 now indicates, on the graduations 55 of the cylinder 50 the rough adjustment of the shaft 33.

In order to obtain a more exact adjustment, the finger is removed from the button 71, thus allowing the pinion 67 to slide under control of the spring 74 into engagement with the fixed gear teeth 45 of the fixed gear 40. The indicating disc 60 is then rotated backward or forward as may be necessary, using for a handle the projection 63. The index 57 now registers with the graduations 62 on the indicating disc 60 to indicate the more exact adjustment. A ratio of 91 to 1 may readily be obtained between the movement of the indicating disc 60 and the shaft 33 using a movable gear 53 with 91 teeth and a fixed gear 40 with 90 teeth, by way of example.

For still finer adjustment, the button 71 may be turned on its own axis, and the reading taken by observing the index 73 and the graduations 66. This movement of the pinion 67 causes rotation of the movable gear 53, a ratio of $341\frac{1}{4}$ to 1 being readily obtained by using a pinion having 24 teeth.

In the modified form shown in Figures 6, 7 and 8 inclusive, parts are identified by the reference numerals of Figures 2 to 5 inclusive, but with 100 added thereto. Thus, for example the fixed gear of Figure 7, bearing reference numeral 140 corresponds to the gear 40 of Figure 3. It is thought that a brief description of the modified form will therefore be ample.

Referring to Figure 7, there is shown a shaft 133 (see Figure 1), and a fixed gear 140. Rotatably positioned within the gear 140 is a movable gear element comprising an indicating cylinder 150, a hub 151 and a gear wheel 153. The teeth of the fixed gear 140 and of the movable gear 153 are cut with the same cutter, with equal pitch cylinder, but the movable gear has a greater number of teeth than the fixed gear, preferably one tooth more.

An indicating disc 160 is provided, with a bevelled edge, and having graduations 162. Pivottally mounted on the lower face of the disc is a pinion 167, in an eccentric position and in constant mesh with the teeth of the gears 140, 153, and having its teeth cut with the same cutter, and its pitch cylinder substantially in alignment therewith, at the point where the teeth are in mesh.

For maintaining the hub 151 in position on the shaft 133 there is provided a friction band 180, preferably of soft rubber. A metal nipple 181 having a bore for the shaft 133, is screwed into the hub 51, and has a thumb screw 183 crimped thereto.

The mounting and operation of the modified form shown in Figures 6 to 8 inclusive,

will, it is thought, be clear from the foregoing description. The indicating disc 160 is rotated to the extent necessary to obtain the desired adjustment. Rotation of the indicating disc moves the pinion 167 with respect to the fixed gear 140 and thus causes rotation of the pinion on its own axis. The pinion 167 being also in mesh with the movable gear 153, the latter is rotated causing the shaft 133, to which it is secured by the compressed friction band 180, to rotate also. With 40 teeth in the fixed gear, 41 teeth in the movable gear 153 and 34 teeth in the pinion, I have obtained a very sensitive adjustment of the shaft 133.

Thus it will be seen that I have provided a dial control particularly suitable for highly sensitive radio receiving sets, which may readily be adjusted to receive a desired signal, and which may be reset whenever desired to a desired adjustment quickly and accurately. The dial is of simple and sturdy construction and can be readily mounted upon a panel by means of a minimum number of holding screws and without the use of a screw driver or wrench. The movable elements of the improved dial control are fastened to the utility in a positive way, without any danger of injuring the shaft of the utility and without throwing the shaft out of alignment by side cramping or uneven strains.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

What is claimed is

1. In a dial control for radiant energy receiving systems, a fixed toothed gear, a rotatable toothed gear secured to a utility to be controlled and having an index to indicate the extent of its movement, and a pinion loosely mounted on said rotatable gear and slidable along an axis parallel to the axes of said gears and having its pitch cylinder in alignment with the pitch cylinders of said gears.

2. In a dial control for radiant energy receiving systems, a fixed toothed gear, a movable gear element secured to a utility to be controlled by the dial, and a pinion selectively slidable into mesh with said gears and having its pitch cylinder in alignment with the pitch cylinders of said gears, and mounted for rotation on the movable gear element so as to mesh with the teeth of the fixed gear.

3. In a dial control for radiant energy receiving systems, a fixed toothed gear, a rotatable toothed gear secured to a utility to be

controlled and having graduations thereon to indicate angular displacement thereof with respect to the fixed gear, and a pinion selectively slidable into mesh with said gears and having its pitch cylinder in alignment with the pitch cylinders of said gears.

4. In a dial control for radiant energy receiving systems, a fixed toothed gear, a rotatable toothed gear secured to a utility to be controlled and having graduations thereon to indicate angular displacement thereof with respect to the fixed gear, and a pinion selectively slidable into mesh with said gears and having its pitch cylinder in alignment with the pitch cylinders of said gears.

5. In a dial control for radiant energy receiving systems, the combination of a stationary gear having a predetermined number of teeth, and predetermined pitch diameter, a movable gear in axial alignment therewith and having the same pitch diameter but a relatively greater number of teeth, and secured to the utility to be operated, a pinion slidably mounted on the movable gear, and means for sliding said pinion to engage selectively one or both of said gears.

6. In a dial control for radiant energy receiving systems, a fixed toothed gear, a movable gear element secured to a utility to be controlled, a dial and a pinion selectively slidable into mesh with said gears and having its pitch cylinder in alignment with the pitch cylinders of said gears, and mounted for rotation on the dial so as to mesh with the teeth of the fixed gear.

7. In a dial control for radiant energy receiving systems, the combination of a stationary gear having a predetermined number of teeth, a movable gear concentric therewith and having one more than said number of teeth, and secured to the utility to be operated, a pinion rotatably mounted on the movable gear in mesh with said stationary gear and movable longitudinally with respect thereto into a desired one of two positions, and a yielding element for normally maintaining the slidable pinion in one of its positions.

8. In a dial control for radiant energy receiving systems, a fixed toothed gear, a rotatable toothed gear secured to a utility to be controlled, said gears having a relatively different number of teeth, and having an index to indicate the extent of its movement, and a pinion longitudinally slidable into mesh with said gears and having its pitch cylinder in alignment with the pitch cylinders of said gears, the teeth of said gears and said pinion having substantially the same pitch.

9. In a dial control for radiant energy receiving systems, the combination of a stationary gear having a predetermined number of teeth and predetermined pitch diameter,

a movable gear in axial alignment therewith and having the same pitch diameter but a relatively greater number of teeth and secured to the utility to be operated, a sliding 5 pinion to engage selectively said gears, and manual means for sliding said pinion longitudinally.

10. In a dial control for radiant energy receiving systems, the combination of a stationary gear having a predetermined number 10 of teeth, a movable gear concentric therewith and having one more than said number of teeth, and secured to the utility to be operated, a slideable pinion to engage selectively 15 said gears, manually controlled means for sliding said pinion longitudinally, and a yielding element for normally maintaining the slideable pinion in one of its positions.

11. In a dial control for radiant energy receiving systems, the combination of a stationary gear having a predetermined number 20 of teeth, a movable gear concentric therewith and having a relatively different number of teeth, and secured to the utility to be 25 operated, a dial, a pinion having an axis parallel to but spaced from the axis of said dial, said pinion being slidably mounted on the dial to engage selectively said gears, a yielding element for normally maintaining 30 the slideable pinion in one of its positions, and manually operable means for moving the pinion into another of its positions.

12. A control device comprising a frame having teeth to form a fixed gear and including spaced lugs whereby the frame may 35 be maintained in fixed position and having a portion cut away to form a sight hole, an indicating cylinder rotatably mounted adjacent the fixed frame provided with portion 40 thereof observable through said sight hole and having a hub portion, said hub portion having a partly screw-threaded recess, a movable gear mounted on said indicating cylinder, an indicating disc rotatably mounted on said hub and having a projection eccentrically positioned thereon, a slideable pinion mounted in said projection to engage said fixed gear and said movable gear 45 selectively, an operating button for moving said pinion, a spring mounted within said projection for maintaining said pinion normally in one position, a friction band within the recess of the hub for securing the indicating cylinder to the utility, and a nipple for 50 maintaining said indicating disc in fixed longitudinal position and for compressing said friction band.

13. A control device comprising a frame having teeth to form a fixed gear and including spaced lugs whereby the frame may 55 be maintained in fixed position and having a portion cut away to form a sight hole, an indicating cylinder rotatably mounted adjacent the fixed frame, a portion thereof being observable through said sight hole, and having a hub portion, said hub portion having a partly screw-threaded recess, a movable gear mounted on said indicating cylinder, an indicating disc rotatably mounted on said hub, a pinion mounted on said disc to engage 60 said fixed gear and said movable gear, a friction band within the recess of the hub for securing the indicating cylinder to the utility, and a nipple for maintaining said indicating disc in fixed longitudinal position 65 and for compressing said friction band.

14. A control device comprising a frame having teeth to form a fixed gear and including spaced lugs whereby the frame may 70 be maintained in fixed position and having a portion cut away to form a sight hole, an indicating cylinder rotatably mounted adjacent the fixed frame, said cylinder being observable through said sight hole, and having a hub portion, said hub portion having a partly screw-threaded recess, a movable gear mounted on said indicating cylinder, a separable stop member carried by said cylinder so as to contact with said lugs to limit the 75 movement of the cylinder with respect to the fixed frame, an indicating disc rotatably mounted on said hub and having a projection eccentrically positioned thereon, a slideable pinion mounted in said projection to engage said fixed gear and said movable gear 80 selectively, an operating button for moving said pinion, a spring mounted within said projection for maintaining said pinion normally in one position, a friction band within the recess of the hub for securing the indicating cylinder to the utility, and a nipple for maintaining said indicating disc in fixed 85 longitudinal position and for compressing said friction band.

15. A control device comprising a frame having teeth to form a fixed gear and including spaced lugs whereby the frame may 90 be maintained in fixed position and having a portion cut away to form a sight hole, an indicating cylinder rotatably mounted adjacent the fixed frame, said cylinder being observable through said sight hole, and having a hub portion, said hub portion having a partly screw-threaded recess, a movable gear mounted on said indicating cylinder, a separable stop member carried by said cylinder so as to contact with said lugs to limit the movement of the cylinder with respect to the fixed frame, an indicating disc rotatably mounted on said hub and having a projection eccentrically positioned thereon, a slideable pinion mounted in said projection to engage said fixed gear and said movable gear 95 selectively, an operating button for moving said pinion, a spring mounted within said projection for maintaining said pinion normally in one position, a friction band within the recess of the hub for securing the indicating cylinder to the utility, and a nipple for maintaining said indicating disc in fixed longitudinal position and for compressing said friction band.

Signed at New York, in the county of New 105 York and State of New York, this ninth day of November, A. D. 1925.

FRANK E. HALLORAN.
